UNITED STATES PATENT OFFICE.

THOMAS McDONOUGH, OF MONTCLAIR, NEW JERSEY.

HOIST OR ELEVATOR.

SPECIFICATION forming part of Letters Patent No. 278,445, dated May 29, 1883.

Application filed February 13, 1883. (No model.)

To all whom it may concern:

Be it known that I, THOMAS McDONOUGH, a citizen of the United States, residing at Montclair, in the county of Essex and State 5 of New Jersey, have invented Improvements in Hoists or Elevators, of which the following is a full, clear, and exact description.

The purpose of my invention is to prevent the car from falling should the hoisting-rope break, by having a cross-beam directly beneath the car and attached to it at the center of the beam, the ends of which rest all the time on solid supports built in the sides of the shaft or well in which the car is raised and lowered.

15 The drawing accompanying this specification represents the car C and two side guides, as seen from below, looking upward at its bottom. The front and back guides, or long timbers between which the car moves, are not 20 represented in the drawing. A cross-beam, B, hangs below the car from a bolt fastened to the car-bottom at its middle, on which the beam revolves, and also slides up and down a few inches. When it slides up on the bolt it 25 jams against the timbers of the car and cannot revolve; but when it is kept a few inches below the car it can revolve freely. A spring, sufficient to counteract the weight of the beam, tends at all times to keep the beam up 30 against the car-bottom, and the lever L, which has one end pressing upon the beam and its outer end connected by a cord with the hoisting-rope above the car, (so long as there is tension on the rope,) will overpower the spring 35 and keep the beam away from the car. When the rope breaks or falls the strain on the outer

end of the lever is removed and the beam rises up or the car falls against it. I prefer to attach the hoisting-rope to the car with a few links of chain, so that in case of breakage the 40 strain on the lever may be got rid of before the car has time to begin falling, and be stopped more quickly by the beam moving up against it than if it fell a few inches onto the beam. The ends of the beam B are forked over two 45 spirals built firmly into the walls of the hoist-way throughout its height, and marked S S. The corner guide-timbers, wherever the spirals pass them, are recessed, or else the spirals are cut away at the posts to allow the guides on 50 the car to slide past. The drawing shows the former plan, and uninterrupted spirals are set in recesses in the posts. The movement resulting from this arrangement of a beam hanging beneath the car is as follows: When the 55 weight of the car is properly held by the hoisting-rope the beam revolves on the spiral guides or supports, as it freely follows the movement of the car up and down; but when the rope breaks the car and beam are instantly interlocked, and both are prevented from moving, 60 the car being held up by the beam, the ends of which rest on firm supports.

What I claim, and desire to secure by Letters Patent of the United States, is— 65

The combination of the beam B with the spirals S S and the lever L, substantially as described.

THOMAS McDONOUGH.
